MULTIPLYING MACHINE

James M. Cunningham, Endicott, N. Y., assignor
to International Business Machines Corpora-
tion, New York, N. Y., a corporation of New
York

Application June 4, 1935, Serial No. 24,789

2 Claims. (Cl. 235—61.8)

The present invention relates to multiplying machines and more specifically to machines of the record card controlled type.

The principal object of the invention is to provide improvements in such machines whereby problems of greater complexity may be solved.

A more specific object of the invention is to provide means for evaluating the equations

10 $C - [A + (A \times B)]$, $C - [A - (A \times B)]$,
 $[A + (C \times B)] - C$ and $[A - (C \times B)] - C$

where A, B and C are amounts derived from a record card and to enter the result back on the card.

15 A further object of the invention is to provide means for testing the resulting value to determine whether it is in the form of a true number, a complement, or zero and to control the subsequent operation of the machine accordingly.

20 A further object of the invention is to provide means for entering a so-called "elusive one" into the units order of an accumulator in advance of the entry of a nines complement therein.

25 A still further object resides in the provision of a plurality of successive "elusive one" entries into an accumulator equal in number to a pre-determined number of subsequent nines complement entries.

30 A further object resides in the provision of switching devices whereby the machine may be readily converted from a "standard" multiplying machine to one capable of performing special computations involving the solution of equations.

35 Various other objects and advantages of the invention will be obvious from the following particular description of one form of mechanism embodying the invention or from an inspection of the accompanying drawings; and the invention also constitutes certain new and useful features of construction and combination of parts hereinafter set forth and claimed.

In the drawings:

40 Figs. 1a, 1b, and 1c, taken together and placed one above the other in the order named, constitute a wiring diagram of the electric circuits of the machine.

45 Fig. 2 is a diagrammatic representation of the various units of the machine showing the manner in which they are interconnected for the computation of equations of the form

50 $C - [A + (A \times B)]$ and $C - [A - (A \times B)]$

55 Fig. 3 is a similar diagram showing the connections for the computations of equations of the form $[A + (C \times B)] - C$ and $[A - (C \times B)] - C$.

Figs. 4a and 4b, taken together, represent a timing diagram of the essential circuit controlling elements of the machine.

Fig. 5 is a diagrammatic representation of a portion of the readout section of the SP accumulator.

Fig. 6 is a detail of mechanism for entering a "one" in the units order of an accumulator.

Fig. 7 is a partial section through one of the accumulators.

10

Standard operation

Before explaining the manner in which the machine operates in the computation of the various equations outlined in Figs. 2 and 3, a brief 15 explanation will be given of the manner in which the machine operates in performing simple multiplying operations. The mechanical structure of the machine is substantially the same as that of Patent No. 1,933,714, granted November 7, 1933 20 to J. M. Cunningham, and in Patent No. 1,944,665, granted January 23, 1934, to D. J. Oldenboom.

After the record cards bearing perforations representative of the factors to be multiplied have been placed in the feed magazine of the machine and after the various preliminary plug connections have been made for directing the entries into the accumulators, the main line switch SW (Fig. 1c) is closed, which places the motor M in operation. The motor M drives the 25 AC—DC generator, indicated at AC and DC, Figs. 1a and 1c, respectively. The DC portion of the generator supplies current to DC lines 10 and 11 (Fig. 1c) and the AC commutator supplies current to ground and to a line 12. The 30 start key contacts 13 (Fig. 1c) are now closed by depression of the start key button, which completes a circuit from the DC line 10, through a relay coil C, contacts 13 (now closed) (196 of Patent 1,944,665), upper contacts G1, cam contacts FC2, to line 11. The coil C establishes a 35 holding circuit through its contacts C2 and cam contacts FC8.

The coil C, when energized, also closes a pair of contacts C1, which will complete a circuit from line 10, normally closed relay contacts F1, card feed clutch magnet 14 (222 of Patent 1,944,665), cam contacts FC6, stop key contacts 15 (197 of Patent 1,944,665), relay contacts N1, contacts C1, a pair of contacts 16 (P—1 of Patent 1,944,665), 40 to line 11.

45 Energization of card feed clutch magnet 14 will cause withdrawal of a card from the magazine and will advance it to the analyzing brushes 17 (Fig. 1a). During this movement of the card, 50 55

the usual card lever is engaged to close card lever contacts 18 (Fig. 1c) (112 of Patent 1,944,665) which complete a circuit from line 11, contacts 18, relay magnet H, to line 10.

5 In starting up the machine, it is necessary to hold down the start key to maintain the contacts 13 closed during the first complete card feeding cycle, or alternatively, to depress the start key a second time. At the beginning of the 10 second card cycle the closure of cam contacts FC11 will energize relay magnet G through a circuit including card lever contacts 18. Relay magnet G will close its normally open contacts G1, setting up a holding circuit through cam contacts FC2 and will also close relay contacts G2 to provide a further holding circuit through the card lever contacts 18. These two holding circuits alternate in maintaining relay magnet G energized as long as cards continue to feed from the magazine. The relay magnet H is also provided with a holding circuit which extends through card lever contacts 18 or serially through relay contacts G2 and cam contacts FC2.

20 Energization of relay magnet H will cause shifting of its contacts H1 (Fig. 1a) to the reverse of the position shown, thereby supplying current to the impulse distributor 19 (188 of Patent 1,944,665) which supplies current through contacts FC1 (closed in the first half of the card 25 feed cycle) to the analyzing brushes 17 and as the card proceeds past the analyzing brushes, circuits will be completed to the accumulators selected to receive entries in accordance with the 30 perforations in the record card; that is, as the card traverses the brushes 17, the multiplier factor will be entered into the multiplier accumulator and the multiplicand factor will be entered into the multiplicand accumulator.

35 The entering circuits extend from the AC generator, through line 12, to the now closed contacts H1, cam contacts FC1, distributor 19, brush contact roll between which and the brushes 17 the card passes. From the contact roll the circuits extend through the perforations in the card, the 40 brushes 11, to plug sockets 20, from which suitable plug connections are made to sockets 21 and sockets 22 of the multiplier and multiplicand accumulators, respectively, to effect energization of the adding magnets 23 (213 of Patent 45 1,944,665) of the related accumulators. The entering circuit, after passing through the magnets 23, continues through normally closed contacts A2 to ground.

45 After the first card has traversed the brushes 50 17 it is fed into the punching unit of the machine and upon its arrival there, it causes closure of punch card lever contacts 24 (120 of Patent 1,944,665) (Fig. 1c) which cause energization of the relay magnet F. The closure of the normally 55 open contacts F1 establishes a circuit from line 10, through now closed contacts F1, cam contacts CC3, trip magnet 25 (143 of Patent 1,944,665) of the punching unit which functions to trip clutch mechanism to further advance the 60 card to punching position. The circuit continues through eject contacts 26 (P-3 of Patent 1,944,665) and relay contacts K1, which at this time are in the position reverse to that shown. The contacts K1 are controlled by relay magnet K which 65 is energized through last column contacts 27 (P-5 of Patent 1,944,665) in the punching unit. These so-called last column contacts close whenever the card advancing carriage of the punching unit is in last column punching position, which 70 position it occupies when the operation of the 75

entire machine is first started so that upon starting, relay K is energized and its contacts K1 are in shifted position.

75 The cards are handled in the card punching unit in the customary manner as set forth in the above mentioned patents. After the analyzed card has been advanced column by column in the punching unit and the left hand component accumulator LH is being reset, a circuit is completed which extends from line 11 (Fig. 1c), upper 10 contacts 44 (129 of Patent 1,944,665), 80 operated similarly to contacts 44 and 79 which are closed while the LH accumulator is resetting, switch TP2 (in dotted line position), wire 28 (Figs. 1b and 1a), through relay magnets M and N in parallel, wire 29 (Figs. 1b and 1c), to line 10. Relay magnet M closes its contacts M2 (Fig. 1a) to provide a holding circuit for the relays extending from line 10, wire 29, relays M and N, contacts M2, wire 30, to the normally closed contacts 31 (195 of Patent 1,944,665) (Fig. 1c) and line 11. Contacts 31 are opened during the operation wherein the MC accumulator is reset and until such time, relay magnets M and N will remain energized. These are the master relay magnets 25 of the cycle controller unit and they call the cycle controller into operation to determine the location of significant figures in the multiplier. The circuit through wire 28 also extends to the zero segments of the readout unit of the multiplier accumulator designated MPRO. If any of the brushes of the MPRO stand at zero, selected ones of the column skip magnets 32 will be energized according to which denominational orders of the multiplier contain zeros. The magnets 35 32 control contacts 32a through which circuits are completed to the column shift relay magnets 33 and to the multiplying relay magnets 34. The magnets 32 and 33 correspond to the magnets designated Y and CS in the Cunningham patent 40 referred to.

45 In those positions in which the multiplier digit is zero, the associated magnet 32 will be energized and the related contacts 32a (Yu, Yt, etc. of Patent 1,944,665) will be shifted from the 50 position shown in the diagram so that the related magnet 33 will be disconnected from the circuit which is traceable from line 12, cam contacts CC2, relay contacts M1, normally closed contacts 32a, relay magnet 33 through the appropriate 55 readout spot in one order of the readout section MPRO, to the corresponding relay magnet 34 (X1, X2, etc. of Patent 1,944,665), and thence to ground. The function of the contacts 32a is to ground. The function of the contacts 32a is to direct the multiplier relay selecting circuits 60 through only those positions in which significant figures occur in the multiplier and to skip the positions in which zeros occur. With a particular magnet 34 energized, for example the X5 magnet 34, the related contacts shown in the 65 center of Fig. 1a will become closed and with the emitter 35 (185 of Patent 1,944,665) in constant operation, impulses will be emitted through the contacts of the X5 multiplier relay 34 and thence through the readout device of the multiplier accumulator designated MCRO and thereafter through the column shift relay contacts CSL and CSR (Fig. 1b) to the adding magnets 70 23 of the RH and LHA accumulators which thus receive the right and left hand partial product entries. The CSL and CSR relay contacts are controlled by the relay magnets 33 and serve to effect the proper denominational allocation of the partial product entries. Thus, when multiplying is being effected by the units digit of the 75

multiplier, the units magnet 33 is energized and the units order set of contacts CSL and CSR are closed.

Energization of a relay magnet 33 (Fig. 1a) 5 will also close a pair of contacts 33b (CSu—3, CSt—3, etc. of Patent 1,944,665) which will cause energization of the relay magnet 32 in the order in which multiplying is taking place. This in turn will shift the related pair of contacts 32a 10 so that when cam contacts CC2 again close, the aforetraced circuit will be directed through the magnet 33 in the order containing the next higher significant figure and will skip the magnets 33 in positions in which zeros are present.

15 The machine continues multiplying operations during which the partial products are entered in succession into the LHA and RH accumulators. After multiplying cycles have been effected for all significant multiplier digits, all of the magnets 20 32 will have been energized and all of the contacts 32a will be in their shifted positions so that on the next following cycle the closure of cam contacts CC2 will complete the circuit which extends through all of the now closed contacts 32a 25 to the relay magnet 36 (1CR of Patent 1,944,665) and the multiplicand reset magnet 37MC (223MC of Patent 1,944,665). A parallel circuit also extends through cam contacts FC10 and multiplier reset magnet 37MP (223MP of Patent 1,944,665). 30 If switch 38 is open, the multiplier accumulator will not be reset and the factor therein will become a so-called "fixed" multiplier for succeeding multiplying operations. The relay magnet 36 closes its contacts 36a (Fig. 1b) which connect the readout section of the RH accumulator, designated RHRO, to the adding magnets 23 of the LHA accumulator, thus transferring the sum of the right hand partial products into the LHA accumulator to produce the complete product. 35 These circuits are controlled from the emitter 39 through a group of wires generally designated 39 which extend to the readout device RHRO.

In Fig. 7 is shown a section of an accumulator to illustrate the mechanical arrangement of the 40 readout section which is the same for all the accumulators except in the number of commutator segments provided. For each order there are 45 commutator segments 100 which are electrically connected through the brush structure 101 to the common arcuate conducting strip 102. The position of the brush corresponds to the value entered on its associated accumulator and connects the segment 100 having such value to strip 102. In the circuit diagram the segments and 50 strips are represented as circles and vertical bars respectively.

During the cycle in which the MC accumulator is reset concurrently with the RH to LH transfer operation, the normally closed contacts 31 (Fig. 55 1c) which are operated by a cam on the MC reset shaft will open to interrupt the circuit to the cycle controlling relay magnets 32, thus causing deenergization of all these magnets and the interruption of their related circuits.

60 The RH to LH transfer relay magnet 36 closes a pair of contacts 36b (Fig. 1a) (1CR—17 of Patent 1,944,665) through which a circuit is completed by the emitter after the amount in the RH accumulator has been transferred to the LHA accumulator. This circuit is traceable from line 65 12 through emitter 35, which, when the brushes are at the zero segment, will continue through contacts 36b to the reset magnets 37RH (223RH of Patent 1,944,665) which function to initiate resetting of this accumulator.

Referring now to Fig. 1c, the contacts 40 are closed along with the shifting of contacts 31 when the MC accumulator is resetting, thereby completing a circuit from line 11, contacts 40, switch TP1 in dotted position, relay magnet C. 5 to line 10. Relay magnet C establishes a holding circuit through contacts C2 as before and also closes contacts C1 to complete the circuit through the card feed clutch magnet 14 as traced above. This causes the next card to be fed to the analyzing brushes where the new factors will be entered into the accumulators and in the case of fixed multiplier operation, wherein the multiplier accumulator is not reset, only a multiplicand factor will be entered into the MC accumulator in 10 preparation for the next series of multiplying operations.

During the operation of card feeding, the cam contacts FC4 close, completing a circuit from line 11, switch TP6 in dotted line position, contacts FC4, to plug socket 41, thence through a plug connection 42 to a socket 43, relay B, to line 10. The plug socket 43 is of the split socket type, which, when no plug is inserted, forms a connection between relay B and cam contacts CC4. The insertion of a plug will split the socket permitting connection between plug connection 42 and relay magnet B and at the same time breaking the connection between magnet B and contacts CC4. Energization of magnet 30 B will close its contacts B2 to provide a holding circuit through normally closed contacts 44 associated with the reset devices of the LHB accumulator. The magnet B will also close its contacts B1, thereby establishing a circuit from line 35 11, contacts B1, contacts 45 (154 of Patent 1,944,665) in the punching unit, switch 46, wire 47 (Fig. 1b) to the common conducting strip 48 (613 of Patent 1,933,714) of the punch column selector. 40

The strip 48 is connected in succession to the segments 49 (612 of Patent 1,933,714) as the record card moves step by step past the column of punches in the punching unit and in those columns which are plug connected to the readout 45 device LHARO will complete circuits from segments 49 to sockets 50, thence through plug connections to sockets 51 and through the LHARO device to wires 52 which extend to the punch selecting magnets 53 (792 of Patent 1,933,714) 50 whose common return wire 54 extends to line 10.

While the step by step punching of the product takes place in the card, the new factors are entered into their appropriate accumulators and when the card is completely punched and advanced to its last column position, relay K will be energized as before to close its normally open contacts K1 and complete a circuit through the eject magnet 55 (151 of Patent 1,944,665) which ejects the punched record from the machine. 60 As explained in the above mentioned patents, the energization of any of the magnets 53 will advance a related interposer into operative relationship with a corresponding punch and the advancement of any interposer will cause closure 65 of a pair of contacts 56 (805 of Patent 1,933,714) (Fig. 1c) which complete a circuit from line 10, through the punch magnet 57 (804 of Patent 1,933,714), contacts 56 and B1, to line 11. The punch magnet serves to press the interposer 70 against the selected punch to effect a perforation in the corresponding position in the card column. The feeding of the new card to the brushes will again cause closure of the card lever contacts 18, causing energization of magnet H to 75

permit the impulse distributor 19 to supply current to the card analyzing brushes 17. The machine is arranged to permit so-called "group multiplication" in which the multiplication of a multiplicand factor is effected by a common multiplier factor carried by a so-called "rate" card. In this type of operation the usual multiplier list contacts 100 (Fig. 1c) function to prevent punching in the "rate" card. As this type of 10 operation is not involved in the present invention, further mention thereof will be omitted.

The operation of the machine as thus far described is substantially the manner in which multiplying operations are performed in the patents 15 referred to and in commercial machines and the timing of the essential contact devices is as indicated on the timing chart, Figs. 4a and 4b. The improvements incorporated in such machines whereby the additional problems mentioned here- 20 tofore may be handled will now be described in connection with the circuit diagram and the dia- 25 grammatic representations in Figs. 2 and 3. Each of the four problems is capable of solution by the machine and each requires a slightly different arrangement of plugging connections. They will therefore be dealt with separately. For the solution of these problems switches TP1 to TP7 are shifted to their full line positions as indicated on the circuit diagram.

30

PROBLEM

$$C - [A + (A \times B)]$$

Referring to Fig. 2, record cards bearing 35 perforated data in fields A, B, and C are placed in the feed magazine of the machine and it is desired to compute the product $A \times B$, the sum $A + (A \times B)$, and the difference $C - [A + (A \times B)]$ and to punch the results obtained back in other 40 fields of the record card. The sockets 20 associated with the brushes 17 which read the amount B are connected to sockets 21 on the MP accumulator through plug connections represented by the line 60.

45 It may be mentioned at this point in connection with Fig. 2 that the heavy solid lines represent plug connections between the brushes and the accumulators and the heavy dotted lines represent plug connections between the punches and the readout devices of the accumulators, and the lighter solid lines represent fixed wiring in the machine.

The plug sockets 20 associated with the field 50 in which the A amount is punched are connected to sockets 22 in the MC accumulator through plug connections 61 and also through plug connections 62 to plug sockets 63 which are wired to normally closed relay contacts CLA1 and through normally closed contacts CLC1 to the entry devices of the 55 LHB accumulator. Sockets 20 associated with the brushes which sense the C amount are connected through connections 64 to sockets 65 which are wired to normally closed contacts CLB1 extending through entering devices of the five lowest 60 order positions of the SP accumulator and through parallel connections 66 are entered in duplicate in the five highest orders of the SP accumulator.

As the record card passes the analyzing 70 brushes, entries are made into the MP, MC, LHB and SP accumulators, as indicated, through the connections just traced. Thereafter, multiplying operations ensue in the same manner as explained in connection with the standard operation of the multiplying machine.

The M and N relays are initially energized through a different circuit than when normal multiplying is performed. The circuit is completed during the initial part of card feeding cycles by closure of cam contacts FC14 and is traceable from line 11 (Fig. 1c), card lever contacts 18, cam contacts FC14, switch TP2 (now in full line position), wire 28 to relay magnets M and N and to other side of line as before.

The entries in the MC and MP accumulators 10 are read out to determine the partial products which are thereafter entered through the CSL and CSR devices into the RH and LHA accumulators through the lines indicated at 67 and 68, respectively. Thereafter, the amount standing 15 in the RH accumulator is transferred to the LH accumulator through the line designated 69 so that at this point the LHA accumulator contains the product of A and B. Thus far the operation 20 of the machine is substantially the same as explained under the standard operation, and for the specific problem illustrated in Fig. 2 where A is 150 and B is .00082, the product will be .1230000. In carrying the problem out further, it is not desired to consider the decimal product 25 beyond the second place so that in the further steps of the problem, the figures to the right of the second decimal place are ignored.

There now ensues a transfer cycle of 30 operations during which the amounts standing on the five highest orders of the LHA accumulator are transferred to the LHB accumulator and for this purpose contacts CLA1 are shifted so that the entries may follow through the line designated 35 70 in Fig. 2. The controlling magnet CLA for 35 these contacts is shown in Fig. 1c and is energized upon closure of contacts 40 associated with the MC accumulator reset devices, the circuit being traceable from line 11, contacts 40, switch TP5, relay coil CLA, to line 10. The coil will 40 close its contacts CLA10 to provide a holding circuit extending through contacts CLA10, CC1, the contacts D2, now closed, contacts CLA-9 to line 11.

A second circuit is closed when lower contacts 45 31 make, which energizes the relay magnet D whose contacts D2 provide a holding circuit through contacts CC1 and CLA9. The contacts CC serve to hold the relays CLA and D energized for a period sufficient to enter the transferred 50 amount into the LHB accumulator. The contacts CLA1 are shown in the center of Fig. 1b and are connected through the wires 70 to the readout devices of the five highest order positions of the LHARO device, the five lowest orders 55 having no readout connections for the purpose mentioned. The relay D closes a pair of contacts D1 in the center of Fig. 1b and the relay magnet CLA closes a pair of contacts CLA1, permitting a circuit to extend from line 12, through 60 contacts D1, CLA1, switch TP9, to emitter 71, which is connected to the readout devices of the accumulators through wires 72 in true number relationship; that is, the "9" spot of the emitter is connected to all the "9" commutator segments 65 of the readout devices, the "8" spots to all the "8" segments, and so on, so that the amount standing in the LHARO device will be transferred in true form to the LHB accumulator in the same manner as amounts are transferred from 70 the RH accumulator to the LHA accumulator during standard multiplying operations. Following this entry cycle, there will be contained in the LHB accumulator the amount A plus the product ($A \times B$). This is now to be subtracted 75

from the amount in the SP accumulator or, as subtraction is customarily performed in tabulating machines, added thereto in the form of a complement.

5 Referring to Fig. 2, this transfer operation is diagrammatically represented as extending from the LHBRO device, through wire 73 during the passage through which the amount read out is inverted. In order to complete entry into the SP 10 accumulator, contacts CLB1 must be shifted from the position indicated. The manner in which this is effected is as follows: With contacts CLA8 closed, the closure of contacts CC5 will complete a circuit from line 11, contacts CC5, CLA8, switch 15 TP8, relay magnet CLB, to line 10. Relay CLB will close its contacts CLB8, providing a holding circuit therefor through contacts CC8 so that during the next cycle, when relay magnet CLA is deenergized, magnet CLB will remain energized. The shifting of contacts CLB1, which are 20 shown in Fig. 1b, will serve to connect the adding magnets 23 of the six lowest orders of the SP accumulator to the six readout positions of the LHBRO device through the wires 73. Relay coil 25 CLB closes a pair of contacts CLB7 (Fig. 1b) so that on the next cycle with contacts D1 also closed, a circuit will be traceable from line 12, through contacts D1, contacts CLB7, to emitter 74. This emitter is also known as an inverter in 30 that the commutator spots thereon are connected to the wires 72 in the nines complementary relationship, which causes the number standing in the accumulator to be read out as the nines complement thereof; thus an "8" standing 35 in the accumulator will be transferred to the SP accumulator as a "1"; a "7" as a "2", and so on.

The same entry is also made in the five highest orders of the SP accumulator through wires 66 40 (Fig. 1b).

During the initial card feeding and analyzing cycle, the "elusive one" is entered into the units order of the SP accumulator to complement the same to ten. This is effected by the SP carry 45 magnet 75 (Figs. 1c and 6) which, if a plug connection 76 be made between sockets 41 and 78, will be energized through a circuit extending from line 11, card lever contacts 18, switch TP6, cam contacts FC4 (closed during the card feed 50 cycle, see Fig. 4b), plug socket 41, connection 76, socket 78, carry magnet 75, to line 10.

For the example selected in Fig. 2, the SP accumulator will thus receive the following entries in order.

55 Card entry----- 50000 - 50000
"Elusive one" entry during card cycle----- 1
By complementary transfer----- 84987 9 84987

60 Resulting in the total----- 34988 0 34988

It will be noted that the elusive one in the left hand total is taken care of through a carrying operation from the sixth order to the seventh. 65 If the amount standing in the LHBRO device had been equal to the amount standing in the SP accumulator, the resulting summation would be as follows:

70 Card entry----- 50000 - 50000
"Elusive one" entry----- 1
Complement transferred----- 49999 9 49999

00000 0 00000

75 The entire accumulator would thus cancel out

to zero. If the amount in the LHBRO device were greater than the SP entry, the resulting summation would be as follows, assuming the LHBRO amount to be 55000:

Card entry-----	50000 - 50000	5
"Elusive one" entry-----	1	
Complement transferred-----	44999 9 44999	
	94999 9 95000	10

In this case there is no carry from the sixth to the seventh order and the six lowest orders represent the complement of the credit balance.

In Fig. 5 there is represented diagrammatically the readout section of the seven highest orders 15 of the SP accumulator, the remaining orders being the same as the two shown at the right end of the figure. In the five highest positions only zero segments 100 are provided and in the next adjacent position only the "9" segment 100 20 is required. The "9" segment is tested as will be explained to ascertain the presence of a result in complementary form and the zero segments are tested to determine the presence of a zero balance.

In accordance with the problem of Fig. 2 the 25 SP accumulator contains a true balance in duplicate, this being the result of the evaluation of the Equation $C - [A + (A \times B)]$ and the machine is now ready to punch this amount back in the card as 349.88.

During the cycle in which relay coil CLB is energized, the closure of cam contacts CC6 will complete a circuit from line 11, cam contacts CC6, contacts CLB9, relay magnet S, which closes its contacts S2 to provide a holding circuit through 35 normally closed contacts 44 associated with the LHB reset devices. Relay magnet S closes its contacts S1 which will permit energization of relay magnet B when cam contacts CC4 close, the circuit extending from line 11, contacts S1, 40 CC4, to relay B and line 10.

Relay magnet B closes its contacts B2 to provide a holding circuit and by closing its contacts B1 at the top of Fig. 1c will permit the step-by-step operation of the punch in response to the 45 readings in the several accumulators which have previously been appropriately connected to the columns of the record in which punching is desired.

After punching has been completed and the 50 card advanced to the last column position, closing contacts 27 at the bottom of Fig. 1c, relay K will be energized, closing its contacts K2 at the top of Fig. 1a so that a circuit may be completed upon closure of cam contacts CC2 which is traceable from line 12, through contacts CC2, contacts K2, normally closed contacts L2, switch TP3, to the reset magnets 37LH which function to control resetting of the LHA and LHB accumulators. A further circuit extends from switch TP3 to switch TP1 to the summary accumulator reset magnet 37SP so that this accumulator is reset concurrently with the LH accumulators. Resetting of the LH accumulators is accompanied by a closure of contacts 79, 80 and upper contacts 44 65 all shown in the center of Fig. 1c whereby a circuit is traceable from line 11, upper contacts 44, contacts 80, contacts 79, wire 81, switch TP1, relay magnet C, to line 10. As before, energization of relay magnet C causes feeding of a new card to 70 the analyzing brushes in readiness for repetition of the cycle of operations under control of perforations in the new record card.

As explained above, the entries in the SP accumulator are made in duplicate, one set in the 75

right hand section and the other set in the left hand section. The accumulation of the right hand section is for the purpose of controlling punching and the total standing in the left hand section is sensed to determine the status of the new balance as computed and controls the perforation of special designations in a predetermined column of the card, for example, the 79th column, in accordance with the determined status 5 of this new balance. Specifically, if the new balance is a positive number, a "1" will be punched in column 79. If the new balance is a complement, the record card will be ejected from the machine without punching and if the new balance is zero, indicating that the payment plus 10 the interest amount has equalled the amount of the original loan, a zero is punched in column 79.

The two sections of the SP readout device are 15 separately designated as SARO and SBRO in the lower left hand corner of Fig. 1b and in Fig. 5. 20 Associated with the SPRO device are two plug sockets 82 and 83, the former of which is plug connected as by a connection 84 (see Fig. 2) to the plug socket 50 associated with the 79th column of the card. The socket 82 is wired to contacts R1 of a relay magnet R and the normally closed blade of the contact is connected to the "1" punch selecting magnet while the normally open blade is connected to the zero selecting magnet so that when the 79th column of the card is 25 in punching position, a circuit will be completed through either the "1" or "0" punch selecting magnets 53 accordingly as the relay contacts R1 remain in the position shown or are shifted.

If the reading in the SPRO device is zero in 30 all orders, a circuit will be traceable through the device as follows: from line 10 (Fig. 1c), relay magnet R, wire 85 (Fig. 1b) to the commutator strip 102 in the lowest order of the SBRO device (see also Fig. 5) thence serially through the commutator brushes 101 standing at zero, their associated segments 100 and commutator strips 35 102 and connections 86 to wire 88 (Fig. 1c) contacts B2, lower contacts 44, to line 11. Relay magnet R will shift its contacts R1 thus connecting the zero punch selecting magnet 53 to the socket 82 so that a zero will be punched in the 79th column of the card. If all five positions of the SBRO device do not register zero, the series 40 circuit traced will not be completed and the "1" selecting magnet 53 will remain connected to the socket 82 and a "1" will be punched in the 79th column unless, as will be explained presently, the amount is in the form of a complement.

The highest order of the SARO device is tested 45 to determine if the final result is a complement and if this highest order stands at "9", it is an indication that such is the case. The readout strip 102 of the highest order of the SARO device is connected through a wire 89 to relay magnet E and a circuit is traceable from line 10, relay coil E, wire 89 (Fig. 1b), strip 102 (see also Fig. 5), the "9" commutator segment 100 and brush 50 101 in the corresponding order, wire 90 (Fig. 1c), cam contacts CC9, relay contacts S1, which are now closed, to line 11. Relay magnet E closes its contacts E2 to provide a holding circuit through the normally closed contacts K1.

Energization of relay magnet E will shift 55 its contacts E1 at the top of Fig 1c, so that with switch 46 in its dotted line position, the punch magnet selecting circuits, which normally pass through wire 47, will be interrupted and a circuit will be made directly from line 11, through contacts B1, 45, switch 46, lower contacts E1, now

closed, punch magnet 57, to line 10. In the operation of the punch magnet 57, the card is advanced one step and contacts 45 are momentarily opened. Upon reclosure, the punch magnet is again energized and the card advanced a further step. In this manner, the entire card is advanced in a step-by-step manner through the punching unit of the machine without receiving any punching. Upon arriving at the last column position, it is ejected in the usual manner and resumption of the operation of the machine takes place as before.

Briefly summarizing, if the final result of the computation $C - [A + (B \times C)]$, called the new debit balance is a true number, a "one" will be punched in column 79. If the result is a complementary number indicating a credit balance, the card is ejected with all punching suppressed and if the result is zero, a zero will be punched in the 10 79th column. 20

PROBLEM

$[A + (C \times B)] - C$

After the first run the credit balance cards are 25 sorted out from those punched 1 and zero in column 79 and fed through the machine for a so-called second run. For this operation, switch TP8 (Fig. 1c) is moved to its dotted line position labelled 2-4.

For this run (see Fig. 3) the "cash received" 30 designated A, is read from the card into the LHB accumulator, the old balance, C is read into the MC and SP accumulators and the interest rate B is read into the MP accumulator. A plug connection 92 is made from socket 83 to socket 35 50 associated with the 79th column as indicated in Fig. 3.

After the various amounts have been entered 40 into the accumulators multiplying takes place as during the first run and the amount C is multiplied by the amount B producing the product $C \times B$ in the LHA accumulator. Relay CLA is energized in the same manner as before to close its normally open contacts CLA1 so that the product $C \times B$ is transferred additively to 45 accumulator LHB so that it now contains the value $A + (C \times B)$.

From this amount there is now to be subtracted the amount C standing in the SP accumulator. In Fig. 3 this transfer operation is 50 diagrammatically represented as extending from the SPRO device through wire 93 during the passage through which the amount read out is inverted. To complete the entry, contacts CLC1 must be shifted from the position shown. 55 This is effected due to the shifting of switch TP8 in Fig. 1c so that the circuit, traced above through relay CLB now goes through relay CLC and is held through its contacts CLC8. The contacts CLC1 in parallel with contacts CLB1 supply current to inverting emitter 74 and circuits are completed to the SPRO device through wires 93, contacts CLC1, to adding magnets 23 of the LHB accumulator. 60

To complete the complement the carry magnet 65 94 (Fig. 1c) (similar to SP carry magnet 75) of the LHB accumulator is energized to add the "elusive one" to the units order. To do this a plug connection is inserted between socket 41 and socket 95 so that during the card feeding cycle 70 as before, the LHB carry magnet receives an impulse to enter a "one" in the units order.

In this manner the final result obtains in the LHB accumulator and from this point on punching operations take place in the same manner as 75

for the first run, with the exception that a "2" is punched in column 79 for each card. The circuit involved is traceable from line 10 (Fig. 1c), wire 54, "2" punch selecting magnet 53 (Fig. 1b), wire 96, socket 83, connection 92 (indicated in Fig. 3) to socket 50 of column 79 and thence to other side of line in the familiar manner. The "2" thus punched is indicative of the credit balance.

10 The first run described above is known as the "debit balance run before maturity" and the second run as the "credit balance run before maturity." A third run may be made which is called the "debit balance run after maturity" which is the same as the first run in all respects except for the manner of transferring the product from the LHA accumulator to the LHB accumulator. For this third run the transferred amount is in the form of a complement so that the final result is expressed as $C - [A - (A \times B)]$. The differences reside in shifting switch TP9 (Fig. 1b) to its dotted line position so that the circuit for transferring the product is to the inverting emitter 74 instead of to the true emitter 71.

25 Sockets 41 and 95 (Fig. 1c) are connected and sockets 77 and 78 are also connected to enter "elusive ones" in both the LHB and SP accumulators.

30 The fourth run, called the "credit balance run after maturity" is made with cards rejected during the third run and is exactly similar to the second run except for the change in sign within the brackets of the result $[A - (C \times B)] - C$. Here also switch TP9 is in its dotted line position for complementary transfer. Sockets 41 and 95 are plug connected and socket 77 and a second socket 95 are also plug connected. The LHB accumulator in this wise receives two "elusive one" carry impulses in successive cycles during card feeding operations, one from the FC4 cam and the second from the FC13 cam (see the timing diagram).

Thus when the amounts from the LHA and SP accumulators are entered in the form of complements, there will already be an entry of "2" in the LHB accumulator in the units order.

5 In Fig. 1c are shown contacts designated P2 (corresponding to P2 of Patent 1,944,665) which, when open, interrupt the circuits through contacts J1 and L1 of relay magnets J and L.

10 While there has been shown and described and pointed out the fundamental novel features of the invention as applied to a single modification, it will be understood that various omissions and substitutions and changes in the form and details of the device illustrated and in its operation may be made by those skilled in the art without departing from the spirit of the invention. 15 It is the intention therefore to be limited only as indicated by the scope of the following claims.

What is claimed is as follows:

1. In a machine of the class described, three 20 accumulators, means for entering an amount in each, means for transferring the amounts in each of two of said accumulators in succession to the third in the form of nines complements settable means and means controlled by said settable 25 means and operative in advance of said transferring for entering two elusive ones into said third accumulator.

2. In a machine of the class described, a plurality of accumulators, means for entering an 30 amount in each, means for transferring to one of said accumulators, in succession, and in the form of nines complements, the amounts in each of the other of said plurality of accumulators, settable means and means controlled by said settable 35 means and operative in advance of said transferring for entering into said one accumulator a number of units equal to the number of nines complements to be transferred thereto.

40 JAMES M. CUNNINGHAM.
